UNITED STATES PATENT OFFICE

EDMUND C. MORGAN, OF NEW YORK, N. Y.; OLIVE EUGENIE MORGAN EXECUTRIX OF
SAID EDMUND C. MORGAN, DECEASED

APPARATUS FOR MINING AND LOADING COAL

Application filed November 19, 1917. Serial No. 202,825.

The object of this invention is to provide a more efficient method of mining and loading coal and other material and improved mechanism for carrying on such process.

5 The invention is exemplified in the combination and arrangement of parts shown in the accompanying drawings and described in the following specification and the steps of the process described therein, and the invention is more particularly pointed out in the appended claims.

In the drawings

Fig. 1 is a top plan view of one form of machine included in the present invention.

15 Fig. 2 is a side elevation showing the machine in position in a coal mine.

Fig. 3 is a vertical sectional view on line 3—3 of Fig. 1.

20 Fig. 4 is a vertical sectional view on line 4—4 of Fig. 1.

Fig. 5 is a vertical sectional view on line 5—5 of Fig. 2.

25 Fig. 6 is a vertical sectional view on line 6—6 of Fig. 2.

Fig. 7 is a vertical sectional view on line 7—7 of Fig. 1.

30 Fig. 8 is a vertical sectional view on line 8—8 of Fig. 2.

Fig. 9 is a horizontal sectional view on line 9—9 of Fig. 7.

35 Fig. 10 is an elevation of a supplementary cutter which may be used in connection with the machine shown in Figs. 1 and 2.

Fig. 11 is a top plan view of the cutter shown in Fig. 10 with the cutting chain omitted.

40 Figs. 12, 13, 14 and 15 are diagrammatic views representing different steps in the process of mining coal in which the machine shown in the other views is employed.

The machine, as shown in Figs. 1 and 2, includes a central section A, a forward section B, and a rear section C, the sections B and C being pivotally connected with the 45 central section to swing laterally about upright axes.

As shown most clearly in Fig. 2 of the drawings, the numeral 15 represents the main frame of a mining machine which carries 50 upwardly projecting standards 16 and 17.

A main driving motor 18 is carried on the upper surface of the frame member 15 and is provided with a shaft 19 journaled in a bearing 20 supported by the standard 16. The standards 16 and 17 at their upper ends 55 support a conveyer frame 21 in fixed position relative to the base plate 15 and at the forward end of the plate 15, as shown more clearly in Fig. 4, is a stationary upright shaft 22 which has its lower end secured to the base 15 and its upper end held by the forward portion of the conveyer frame 21. The upright shaft 22 forms a pivotal support for the main frame 23 of the forward section B of the mining machine. The frame member 60 23, as shown in Fig. 4, is bifurcated to form an upper plate 24 and a lower plate 25 which engage the shaft 22. Between the plates 24 and 25 a beveled gear wheel 26 is journaled on the shaft 22 and is driven by a pinion 27 secured to the forward end of the shaft 19. The lower surface of the gear wheel 26 is provided with teeth 28 which mesh with a pinion 29 secured to a shaft 30 which is journaled in the frame 23 and which carries a pinion 31 on its forward end. The pinion 31, as shown in Fig. 8, meshes with a pinion 32 on a countershaft 33 journaled in the frame 23, from which countershaft the mechanism carried by the forward portion B of 65 the machine is driven. The portion B includes the cutting and breaking apparatus for dislodging the coal from its native bed and includes the main frame member 23 which swings about its pivotal support 22 and which carries the cutting and breaking mechanism together with a conveyer for receiving the material as it is dislodged. The frame member 23 has extending around its periphery a chain guide 34 in which the lower cutting chain 35 travels. This chain is driven, as shown in Fig. 4, by a sprocket wheel 36 keyed to the hub of the gear 26. The frame member 23 also carries guideways 37 for a conveyer 38 which receives the material as it is dislodged and carries it rearwardly and discharges it into the conveyer 21 of the central section of the machine. The conveyer 38, as shown in Figs. 4 and 8, is driven by sprocket wheels 39 carried on a 70 75 80

90 95 100

The machine, as shown in Figs. 1 and 2, includes a central section A, a forward section B, and a rear section C, the sections B and C being pivotally connected with the 40 central section to swing laterally about upright axes.

As shown most clearly in Fig. 2 of the drawings, the numeral 15 represents the main frame of a mining machine which carries 50 upwardly projecting standards 16 and 17.

shaft 40 provided with a spur gear 41 meshing with a corresponding gear 42 on the shaft 33. The gear 41 may be thrown into or out of driving connection with the shaft 40 by means of a clutch 43 operated by a hand rod 44 which extends to one side of the machine. The rear end of the conveyer 38 is provided with a pivoted section 45 which extends over the upper portion of the conveyer 21 and is free to be moved upwardly if the section B of the machine is swung to one side a sufficient amount to bring the end of the pivoted section 45 into contact with the upwardly inclined portion of the conveyer 21.

15 The frame member 23 is provided with uprights 46, 47 and 48, each of which carries a threaded standard 49 arranged to telescope into the upper end of its upright. The standards 49 support a frame member 50 which carries a cutter chain 51, the frame and chain constituting an upper kerf-cutter which is adjustable vertically by movement of the standards 49 into and out of their respective supports. Each standard 49 is provided with a sprocket wheel 52 which rests upon the top of its support, and a chain 53 is arranged to drive the sprocket wheels 52 in unison with one another. An idler sprocket 54, Fig. 1, guides one run of the chain 53 to hold the chain out of the way of the material which is being mined. The idler sprocket may be supported from the upright 47. One of the sprockets 52 is provided with a worm wheel 55 rigidly connected therewith by means of which the chain 53 is driven. The worm wheel 55 is rotated by a worm 56 having a crank 57 connected therewith and being supported by a bracket 58 on the upright 46. It is apparent that rotation of the hand crank 57 will rotate the sprocket wheels 52 in which the standards 49 are threaded and thus move the upper kerf-cutter vertically to adjust it to various positions. The cutter chain 51 is driven by a sprocket wheel 59 mounted at one corner of the upper kerf-cutter and rigidly secured to an upright shaft 60 journaled in a bearing 61 which is connected with the frame 50 of the upper kerf-cutter. The bearing 61, as shown in Figs. 7 and 9, is connected with the cutter frame 50 by a bracket 62 which extends laterally on each side of the bearing. As shown in Fig. 8, the shaft 60 is provided with a telescopic extension 63 and the lower end of the shaft 55 is provided with a bevel gear 64 which meshes with a similar gear 65 carried on the end of the shaft 33. By this arrangement the chain 50 may be driven at the various positions of vertical adjustment of the upper kerf-cutter.

60 The forward end of the conveyer frame 21 is provided with a fixed rack segment 66 with which a worm 67 meshes for swinging the cutter section B of the machine laterally about its pivotal support 22. The worm 67 is rigidly connected with a transverse shaft

68 which carries a worm wheel 69 rigidly secured thereto, as shown in Fig. 3. The worm wheel 69 meshes with a worm 70 secured to an upright shaft 71 and mechanism is provided, as shown in Figs. 3 and 8, for imparting two different speeds of rotation to said shaft. The upper end of the shaft 71 carries a pinion 72 meshing with an internal gear 73 loosely mounted on the shaft 60 while a larger pinion 74 meshes with a spur gear 75 also loosely mounted on the shaft 60. The gears 73 and 75 may be selectively connected with the shaft 60 to rotate therewith by means of a clutch 76 having an operating handle 77. It is apparent that different speeds of rotation may be imparted to the shaft 71 by the two sets of gears thus provided and that the cutting section B of the machine will be correspondingly fed laterally about its pivot 22 at speeds depending upon the particular set of gearing which is used.

A breaker is provided to travel in the kerf formed by the upper cutter for the purpose of dislodging the coal and breaking it down onto the conveyer 38. This breaker, as shown in Figs. 1 and 7, comprises a cylinder 80 in which a piston 81 is mounted for reciprocation. The piston 81 is normally held retracted within the cylinder 80 by a spring 82 and when so retracted the piston and cylinder will enter the kerf formed by the cutter-chain 51. The cylinder is provided with a pair of loops 83 which loosely engage a rod 84 connected with the frame member 50 of the upper kerf-cutter and provided with a coiled spring 100 which normally forces the cylinder into a position close to the rear of the cutter-chain. When the piston is forced outwardly by mechanism to be described, the breaker will be held stationary by contact with the coal at each side of the kerf while the cutter continues to feed forwardly. The spring 133 upon the rod 84 will be compressed during this stage of the operation until the breaker has expanded a sufficient amount to dislodge the coal with which it is in contact after which the spring will return the breaker to its normal position. The piston 81 is operated by liquid forced through the pipe 85 into the cylinder 80 by means of a pump 86. The pump 86 is provided with a piston 87 connected by a strap 88 with an eccentric 89 keyed to the shaft 60. The pump is supported by a yoke 90, which passes around the bearing 61 extending through openings 120 in the bracket 62 provided for that purpose. This arrangement permits of the pivotal movement of the breaker relative to the kerf-cutter during the time that the breaker is held stationary while the cutter continues to move forwardly. Liquid is supplied to the pump 86 from a tank 91 provided with the usual valve 92 for controlling the flow of liquid. A check valve 93 is interposed between the pump 86 and the pipe 85 to pre-

5 vent return flow of liquid to the pump, and a three-way valve 94 having an operating handle 95 is placed within the pipe 85 where it unites with branches 96 and 97 leading to the tank 91 and the pump 86 respectively. By means of the valve 94 the cylinder 80 may be connected either with the tank 91 to permit collapse of the breaker, or with the pump 86 to cause expansion of the breaker for dislodging coal.

10 In Figs. 10 and 11 there is shown a supplementary kerf-cutter which may be used to form an upright cut along the arcuate surface described by the outer end of the swinging section B. This kerf-cutter comprises a 15 guide frame 98 in which a chain 99' slides, the frame being curved to correspond to the curvature of the arc through which the cutting mechanism swings. The frame 98 is 20 supported by a pair of bars 99 slidably mounted in a frame 100 carried by a bracket 101 adjustably secured to the upright post 46 by means of a split collar 102 and clamping bolts 103. The bracket 101 carries a motor 25 104 which drives a shaft 105 through gears 106 and 107. The shaft 105 is provided with a sprocket wheel 108 by means of which the chain 99' is driven. The supporting bars 99 may be adjusted within the frame 100 by 30 means of a screw 110 to regulate the tension in the cutter chain 99'. When this mechanism is used in connection with the cutter section B the chain 99' will cut an arcuate kerf between the mine wall and the material being 35 severed which extends from a point adjacent the kerf formed by the lower cutter 35 upwardly toward the kerf formed by the upper cutter 51. The distance between the arcuate edge of the upper kerf and the upper 40 horizontally extending kerf will vary according to the height to which the upper kerf-cutter is adjusted, and the strip of coal remaining between the two kerfs will be broken when the severed section is dislodged by the 45 hydraulic breaker 80. The coal, of course, is broken down by this hydraulic breaker while it is in position above the conveyer 38 and before it is reached by the upright 46, so that it does not interfere with the motor and other 50 mechanism supported by this upright.

When the coal is discharged from the rear end 45 of the forward conveyer, it enters the hopper at the forward end of the conveyer 21 and is moved upwardly by this conveyer 55 until it is discharged into the rear section C of the mining and loading machine. The conveyer 21 is driven by a motor 109 which is geared to a shaft 110 having the usual sprocket wheels for operating the conveyor chain.

60 A pair of screw jacks 111 are carried by the upper portion of the conveyer frame 21 for engaging the roof of the mine to hold the main or intermediate section A of the machine stationary while a cut is being taken. The inclination of the frame 15 may be varied

65 by means of a U-shaped bar 112 pivotally mounted at 113 on the frame and provided with arms 114 which may be rocked by a screw jack 115 to force the bar 112 into engagement with the floor of the mine and thus 70 tip the frame 15 to adjust the position of the swinging cutter. The screw jack 115 is mounted upon the casing of the motor 18, as shown in Fig. 6, which casing also carries a bracket 116 on which is mounted a motor 117 75 driving a winding drum 118 by means of which the machine may be moved forwardly within the mine chamber after each cut is made by the swinging section B.

80 In a machine of this character it is sometimes desirable to remove the motor armature for repairs or other purposes, and because of the position of the motor relative to the other parts it would be difficult to accomplish such removal in the usual way. For this reason the motor casing is split upon 85 a plane passing through the center of the shaft 19 and the two sections are held together by bolts 120. The shaft 19 is provided with a coupling 121. When it is desirable to remove the armature from the motor the coupling 121 is disconnected and the bolts are removed together with the lag screws 122 holding the left side of the motor casing, as viewed in Fig. 6. After this has 90 been done it is comparatively easy to remove one side of the motor casing and roll the armature from its position within the casing.

95 In Figs. 1 and 2 the machine is represented as resting directly on the mine floor but truck 100 wheels 123 are shown in broken lines in these views to indicate the position that such wheels occupy while the machine is being transported into and out of operating position. A track 124 is also indicated in broken lines in these 105 views. This track, of course, is not shown in its true position relative to the mine floor but only indicates the relative position of the mining machine and track during transportation. The usual operation is to bring the machine 110 into position within the chamber while it is supported on its truck wheels 123 resting upon the mine track. After the machine is so positioned, the truck wheels are removed and the frame 15 is permitted to rest upon 115 the floor of the mine chamber. During operation the frame is slid forwardly over the floor of the chamber by the rope winding mechanism 118 and the track is laid in the rear of the machine for accommodating the cars for transporting the mined material.

120 The rear section C comprises a hopper 125 which is pivotally supported at 126 on the frame 15 and which is provided with an alining pivot 127 at the upper portion of the hopper carried by a bracket 128 connected with the conveyer frame 21. A flexible conveyer 129 of usual construction is arranged to travel in the bottom of the hopper 125 and is driven by a motor 130 geared to a 125

cross shaft 131 carrying sprockets 132 for driving the conveyer 129, as shown in Fig. 5.

The diagrammatic views in Figs. 12 to 15 inclusive, illustrate the method of mining coal by using the machine described under difficult operating conditions, such as where a layer of slate is interposed between two layers of coal. Under these conditions the lower vein of coal may be first mined by 10 operating the cutter section B with the upper kerf-cutter in a lowered position, as shown in Fig. 13. After the lower coal has been thus removed, the layer of slate may next be taken out by operating the cutter 15 section with its upper kerf-cutter raised to a position above the upper surface of the slate. During this cut the lower kerf-cutter will move in unison with the upper cutter but will not be required to form a kerf. The slate as it is dislodged may be loaded into a 20 car and hauled from the mine, or it may be discharged into the gob at the side of the mine chamber, as indicated in broken lines in Fig. 12. Where this is done, it will, of course, 25 be necessary to remove a sufficient number of the mine props to permit the discharge section C of the machine to be swung to one side. These props may be replaced after the discharge section is returned to position. In 30 this connection it may be noted that the machine is quite narrow in comparison with the width of the chamber which it opens and the props therefore may be obviously placed at the side of the machine up to within a short 35 distance from the mine face. After the slate has been removed, in the manner indicated in Fig. 14, a third cut may be taken, as shown in Fig. 15, with the upper kerf-cutter raised to a position adjacent the roof of the mine, 40 thus removing the remaining coal above the stratum of slate.

It should be particularly noted that the upper cutter frame 50, as shown in Fig. 1, is provided with a large opening so that material 45 may be dislodged from the space above the cutting section B directly through the opening in the cutter frame 50 onto the horizontal portion of the conveyer 37. For instance, after a section of coal has been mined 50 and loaded in a manner diagrammatically illustrated in Fig. 13, the intermediate layer of slate may in some instances be dislodged manually and permitted to drop through the opening in the cutter frame 50 directly onto 55 the conveyer 37. For this purpose, if desired, the cutter section B may be swung around in accordance with the progress made in the dislodgement of the layer of slate. The loading of the slate will of course occur separately 60 from the loading of the coal. When the foreign material is mined and loaded, it is preferably directed to the gob, as illustrated in Fig. 12 by the dotted lines. It may also occur that in some instances the upper vein 65 of coal, as illustrated in Fig. 15, could be

dislodged and permitted to fall through the opening in the cutter frame 50 onto the conveyer 37. If the vein of coal at the roof is quite thin and may be easily dislodged from the stratum of rock above, it may be more 70 practicable to dislodge the coal manually than to take the time to cut it. Although it is preferable to dislodge an upper layer of material through the opening in the cutter frame 50 onto the conveyer 37, it may be dislodged directly onto the floor of the mine 75 chamber at the arcuate mine wall while the cutter section B is in initial position. Then the dislodged material may be shoveled onto the conveyer 37, or if desired, the under-cutter 80 may be fed through the pile of dislodged material so that the conveyer 37 may be moved under the material and take the latter into the hopper at the lower end of the conveyer 21, the latter taking it in turn into 85 the storage hopper 125.

It should also be noted that both the cutter section B and the rear conveyer section C have a swinging movement on upright axes of 180 degrees or more. The U-shaped frame 90 128 is so associated with the T-shaped extension from the hopper 125 to the shaft 127 that the rear conveyer section C may be swung to positions in alinement with the intermediate conveyer or at substantially right angles 95 thereto at either side of the main frame without interfering in the least with the free passage of material from the conveyer 21 through the opening in the U-shaped frame 128 into the hopper 125.

Attention is also called to the fact that it is preferable to employ separate electric motors 109 and 130 for operating the conveyers 21 and 129 respectively. The conveyer 129 may then be stopped at any time desired while the conveyer 21 may be continued in operation to gradually fill the hopper 125. A separate electric motor is also preferable for the rope winding mechanism 118 shown in Figs. 2 and 6 so that the machine may be pulled forwardly or rearwardly independently of the operation of any of the other motors. The cutter section B is preferably operated by the separate electric motor 18. This electric motor 18 is preferably series wound so that the power exerted thereby will be in accordance with the work to be done, the greater the resistance to feed on account of the condition of the material, the greater the current that will be taken by the motor and therefore 110 the greater the power thereof, as is well understood. Inasmuch as the conveyer 37 is always operated when the cutters operate, and the material is broken down by the breaker 80, no separate electric motor for the conveyer 37 is provided but power is transmitted thereto from the motor 18 by means of the mechanism shown in Fig. 8. However, when desired, the conveyer 37 may be thrown 115 out of operation by releasing the clutch 43 120 125 130

shown in Fig. 8. The clutch 76 is arranged, as shown in Figs. 3 and 8 so that it may occupy a mid-position and therefore when desired, feeding movement may be interrupted 5 while the conveyer 37 is operating and material is being dislodged above the cutter section B through the opening in the cutter frame 50 onto said conveyer 37.

On account of the arrangement of the 10 mechanism for driving the kerf-cutters, the motor 18 may be placed under the conveyer 21 so that the apparatus will be then compact. While the lower or floor cutter chain extends rearwardly under the hopper at the 15 lower end of the conveyer 21, the upper kerf-cutter occupies a position at its rear end in advance of the conveyer 21. Therefore the range of vertical adjustment of the upper kerf-cutter 51 may be increased without interfering with the movement of the pivoted section 45 of the conveyer 37 when the latter is to be swung to positions where the section 20 45 tends to abut against the inclined sides of the conveyer 21.

It should also be noted that the sprocket 25 chain 53 which meshes with the sprockets of the nuts at the upper ends of the posts 46, 47 and 48 is directed by the idler sprocket 54, as shown in Fig. 1, to a position where there will be minimum interference with the free 30 passage of dislodged material through the cutter frame 50. The screw-threaded supports 49 which carry the upper kerf-cutter and which are threaded through the rotary 35 nuts at the upper ends of the spaced-apart upright standards 46, 47 and 48, are simultaneously lifted or lowered so as to secure a rectilinear up and down movement of the upper kerf-cutter together with the breaker 40 80, as shown in Fig. 1.

Obviously those skilled in the art may 45 make various changes in the details and arrangements of parts herein shown and described without departing from the spirit and scope of my invention as defined by the claims hereto appended, and I wish, therefore, not to be restricted to the precise construction disclosed.

I claim:

1. A mining machine comprising a frame, a cutter carried by said frame, a jack comprising a U-shaped bar pivotally connected with said frame, and a lever for tilting said bar about its pivot to adjust the height of a portion of said frame relative to the surface upon which said machine is supported.

2. A mining machine comprising a frame having a base member arranged to rest upon the floor of a mine chamber, a horizontally 50 extending cutter carried by said frame at the forward end thereof, a U-shaped bar having the ends thereof pivotally connected with the rear portion of said frame with the central portion of said bar arranged to engage 55 the floor of the mine chamber, a lever for

tilting said bar about its pivotal connection with said frame, and a screw for operating said lever to tilt said frame vertically to adjust the position of said cutter.

3. In a mining machine, a frame, a horizontally extending cutter pivotally carried by said frame for swinging movement laterally about an upright axis, a second horizontally extending cutter connected with said first cutter and spaced upwardly therefrom, and extensible uprights for supporting said second cutter.

4. In a mining machine, a frame, a cutter head pivotally mounted on said frame to swing laterally about an upright axis, a pair of vertically spaced horizontally extending kerf-cutters carried by said cutter head, an upright kerf-cutter carried by said cutter head substantially in alinement with the outer portions of said horizontally extending cutters, a support for said upright cutter in the rear thereof, and means for dislodging the material partially severed by said cutters to provide clearance for said support as said cutter head is swung about its vertical axis.

5. In a mining machine, a frame, a cutter head pivotally mounted on said frame to swing laterally about an upright axis, a pair of horizontally extending vertically spaced kerf-cutters carried by said cutter head, and triangularly arranged uprights for holding said cutters in spaced relation to one another.

6. In a mining machine, a frame, a cutter head pivotally mounted on said frame to swing about an upright axis, a pair of vertically spaced horizontally extending substantially rectangular-shaped kerf-cutters carried by said cutter head, and a plurality of uprights for holding said kerf-cutters in spaced relation to one another, said uprights being positioned at three of the corners of said rectangular shaped cutters leaving the space between the forward and the outward edges of said cutters open to permit the material being severed to pass between said cutters as said cutter head is swung about its pivot.

7. In a mining machine, a cutter head comprising a pair of vertically spaced horizontally extending substantially rectangular-shaped kerf-cutters, uprights extending between said cutters and located at the inner and rear corners of the rectangle formed by said cutters leaving the space between the forward and outer edges of said cutters free to permit the material being severed to enter between said cutters, a conveyer carried by said cutter head and movable into the kerf formed by the lower one of said cutters, and means for dislodging said material to cause it to be deposited upon said conveyor and transported to a loading position thus providing clearance for the outer upright extending between said cutters.

8. In a mining machine, a cutter head comprising upper and lower kerf-cutters, standards for holding said cutters in spaced relation relative to one another, said standards being arranged inwardly and in the rear of the operating edges of said cutters, and an upright kerf-cutter secured to one of said standards for forming a kerf along the vertical side of the material above and below which the first-mentioned kerf-cutters operate.
9. In a mining machine, a frame, a cutter head pivotally mounted on said frame to swing about an upright axis, a pair of horizontally extending vertically spaced kerf-cutters carried by said head, a standard for holding said cutters in spaced relation, and an upright cutter secured to said standard comprising a cutter chain and a guide for said chain curved to conform to the curvature of the arc described by the outermost portions of said spaced cutters.
10. In a mining machine, the combination with a cutter-frame having the shape of a segment of an annulus, of an endless chain cutter mounted to travel around the perimeter of the annular cutter-frame, and means for pivotally supporting said cutter-frame for arcuate swinging movement on an upright axis.
11. In a mining machine, an upright cutter, means for swinging said cutter about an upright pivot to feed said cutter into the material to be mined, said cutter being curved to conform to the curvature of the arc through which it swings, a support for said cutter positioned in the rear thereof, and means for dislodging said material after it has been passed by said cutter but before it has been reached by said support, thus providing clearance for the passage of said support during the swinging movement of said cutter.
12. In a mining machine, a pivotally mounted cutter head arranged to swing laterally about an upright axis, an upright standard carried by said cutter head, an upright cutter mounted on said standard and curved to conform to the curvature of the arc through which it swings, a motor for driving said cutter connected with said standard in the rear of said cutter, and means for dislodging material adjacent said cutter but in advance of said motor to provide clearance for the passage of said motor during the feeding movement of said cutter head.
13. In a mining machine, a pivotally mounted cutter head arranged to swing laterally about an upright axis, an upright standard carried by said cutter head, a bracket adjustably mounted on said standard, a chain guide carried by said bracket, a cutter chain slidably mounted on said guide, a motor carried by said bracket for driving said chain, and means for adjusting said guide relative to said bracket for regulating the tension of said cutter chain.
14. In a mining machine, a pivotally mounted cutter head arranged to swing laterally about an upright axis, a pair of vertically spaced horizontally extending kerf-cutters on said cutter head, an upright standard connecting said cutters adjacent the outer and rear edges thereof, a bracket carried by said standard, a chain guide carried by said bracket, a cutter-chain slidably mounted on said guide, a motor carried by said bracket for driving said cutter chain, and means for dislodging material adjacent said cutter-chain and guide and between said spaced cutters to provide clearance for said standard and motor when said cutter head is swung about its pivot during a mining operation.
15. In a mining machine, a pair of vertically spaced horizontally extending kerf-cutters, a plurality of adjustable standards for holding said cutters in spaced relation relative to one another, sprocket wheels mounted on each of said standards for adjusting the length thereof, and an endless chain for driving said sprocket wheels in unison with one another.
16. In a mining machine, a pair of vertically spaced horizontally extending kerf-cutters, a plurality of standards for holding said cutters in spaced relation with one another, said standards including threaded sections and sprocket wheels for co-operating with said sections to adjust the length of said standards, an extensible shaft for operating one of said kerf-cutters, and an endless chain for driving said sprocket wheels in unison with one another to adjust the position of said kerf-cutters relative to one another.
17. In a mining and loading machine, the combination with a main frame, of a main conveyer mounted on said frame, a swinging frame mounted on said main frame, kerf-cutting mechanism, breaking mechanism, operating mechanism, and conveyer mechanism mounted on said swinging frame to move therewith, a motor mounted on said main frame below said main conveyer, and gearing for transmitting power from said motor to the said kerf-cutting mechanism and said breaking mechanism, said operating mechanism and the conveyer mechanism on said swinging frame while the latter is swinging.
18. In a mining and loading machine, the combination with a main frame, of a supplemental frame mounted on said main frame to swing on an upright axis relatively thereto, a kerf-cutter mounted on said supplemental frame in position to cut a kerf at the base of a mine wall along the floor of a mine chamber, means for driving said kerf-cutter, means for swinging said supplemental frame to effect feeding movement of said kerf-cutter, dislodging mechanism mounted

on said supplemental frame for vertical adjustment above said floor kerf-cutter and for bodily swinging movement with said supplemental frame, and conveyer mechanism mounted on said supplemental frame to swing bodily therewith in position for automatically receiving the dislodged material and conveying it toward loading position.

19. In a mining and loading machine, the combination with a main frame, of a vertical shaft mounted on said main frame, a swinging frame mounted on said vertical shaft, two kerf-cutters carried by said swinging frame, a gear rotatably mounted on said vertical shaft, means connecting said gear to one of said kerf-cutters, and separate means connecting said gear to the other kerf-cutter.

20. In a mining machine, the combination with a main frame, of a supplemental frame connected thereto, spaced-apart kerf-cutters mounted on said supplemental frame, power transmission gearing for driving said kerf-cutters, power transmission gearing for swinging said supplemental frame on an upright axis relatively to said main frame to effect arcuate feeding movement of said kerf-cutters, and means mounted on said main frame for transmitting power to both of said power transmission gearings to effect the operation of said kerf-cutters.

21. In a mining machine, the combination with a main frame, of a supplemental frame pivotally connected to said main frame to swing relatively thereto on an upright axis, kerf-cutters mounted on said supplemental frame to occupy vertically spaced-apart positions to cut kerfs extending in general horizontal directions at different elevations, driving gearing for said kerf-cutters, means for swinging said supplemental frame on said upright axis to secure arcuate feeding of said kerf-cutters, means mounted on said main frame for transmitting power to said drive gearing and said swinging means to effect the operation of said kerf-cutters, and a source of power on said main frame.

22. In a mining machine, the combination with a main frame, of a supplemental frame connected to said main frame to swing on an upright axis relatively to said main frame, a lower horizontal kerf-cutter comprising a cutter chain extending around said upright axis, an upper kerf-cutter mounted on said supplemental frame with its rear end in front of said upright axis, and means for operating said lower and upper kerf-cutters including swinging movement of said supplemental frame to effect feed of said cutters.

23. In a mining machine, the combination with a main frame, of an upright journal bearing on the forward end of said main frame, a supplemental frame journaled on said bearing for swinging movement relatively to said main frame on the upright

axis of said journal bearing, a gear rotatably mounted on said journal bearing, a motor on said main frame connected to said gear to drive the same, an under cutter mounted on said supplemental frame and comprising an endless cutter chain extending around said upright axis, a driving sprocket wheel connected to rotate with said gear on said journal bearing in position to drive said under cutter, an upper kerf-cutter mounted on said supplemental frame and comprising another endless cutter-chain, means connected between said gear and said upper kerf-cutter for driving the latter, and feed gearing to swing said supplemental frame during the driving of said under and upper kerf-cutters.

24. In a mining machine, the combination with supporting framework comprising spaced-apart upright supports, a kerf-cutter mounted on said spaced-apart upright supports and comprising a cutter-frame rigidly connected to said supports for adjustment in elevation, and means connected to each of said supports for simultaneous operation to move said kerf-cutter up and down rectilinearly to adjust the elevation thereof while maintaining the rigid connection between said upright supports and said cutter-frame.

25. In a mining machine, the combination with supporting framework comprising spaced-apart screw-threaded supports, a horizontal kerf-cutter mounted on top of said supports, means rotatably mounted on said screw-threaded supports to effect the adjustment in elevation of said horizontal kerf-cutter, and mechanism for simultaneously operating said adjusting means.

26. In a mining machine, the combination with supporting framework comprising spaced-apart upright screw-threaded supports, a nut on each support, a horizontal kerf-cutter mounted on said supports, and means comprising an endless sprocket chain for rotating the nuts on said screw-threaded supports to adjust the elevation of said horizontal kerf-cutter.

27. In a mining machine, the combination with supporting framework, of a horizontally extending kerf-cutter pivotally connected to said framework for swinging movement about an upright axis, a second horizontally extending kerf-cutter spaced upwardly from said first-named kerf-cutter, extensible uprights for supporting said second-named kerf-cutter at various elevations, and means for operating said kerf-cutters including arcuate feeding movement thereof on said upright axis.

28. In a mining machine, the combination with a main frame, of a supplemental frame pivotally connected thereto, a motor mounted on the main frame, a worm gear fixed to said main frame, gearing connected between

- said motor and said worm gear for moving said supplemental frame in an arc on said upright axis, a horizontal kerf-cutter comprising an endless cutter chain and a cutter frame mounted on top of said supplemental frame, and power transmission gearing between said motor and said cutter chain for driving the latter.
29. In a mining machine, the combination with a main frame, of a supplemental frame pivotally connected to said main frame to swing relatively thereto on an upright axis, a gear on said main frame rotatable on said upright axis, a motor on said main frame connected to said gear to drive the same, a horizontal kerf-cutter comprising a cutter chain and a cutter frame mounted on top of said supplemental frame, and a train of drive gearing between said first-named gear and said cutter chain and comprising a forwardly extending shaft, a transverse shaft and a vertical shaft.
30. In a mining machine, the combination with a main frame, of a worm gear fixed thereto in stationary position, a supplemental frame pivotally connected to said main frame to move in an arc concentric to said worm gear, a worm on said supplemental frame in position with said worm gear, a horizontal shaft for carrying said worm, a horizontal kerf-cutter mounted on said supplemental frame, means for driving said kerf-cutter, feed gearing connected to said worm to drive the latter slowly to effect slow movement of said kerf-cutter in feeding direction, and mechanism for effecting reversal of said feed gearing and quicker movement of said kerf-cutter to restore the latter to initial position.
31. A mining machine comprising a horizontal kerf-cutter having a cutter frame with a large opening therein for the passage of material dislodged above said kerf-cutter, a plurality of spaced-apart supports for said cutter frame to hold the same at adjusted elevation in substantially horizontal position, adjusting devices on each of said supports, means for simultaneously operating said adjusting devices to secure vertical rectilinear movement of said cutter frame for varying the elevation of said kerf-cutter, and means for supporting said simultaneously operating means to extend along positions leaving the opening through said cutter frame free and unobstructed.
32. In a mining machine, the combination with a main frame, of a supplemental frame pivotally connected to said main frame for swinging movement relatively thereto on an upright axis, kerf-cutting mechanism mounted on said supplemental frame in elevated position, said kerf-cutting mechanism comprising an endless cutter chain mounted on the periphery of a cutter frame having a free and unobstructed opening extending trans-
- versely therethrough for the passage of material dislodged above said kerf-cutting mechanism, means for operating said kerf-cutting mechanism including swinging of said supplemental frame to secure arcuate feeding movement of said kerf-cutting mechanism, and loading apparatus mounted on said main and supplemental frames and comprising a conveyer extending to a receiving position below the said opening in said cutter frame.
33. In mining apparatus, the combination with a wheel supported rigid base frame adapted to run upon the rails of a mine track for transporting the mining apparatus, said base frame being adapted to be lowered to permit the same to rest on and be supported by a mine floor, of a supplemental frame pivotally connected to said base frame to swing laterally relatively thereto, a plurality of upright supports mounted directly on said supplemental frame and extending upwardly therefrom at the angles of a relatively widely extended horizontal polygon, a rigid cutter frame, means carried by and vertically adjustable on said upright supports for carrying said cutter frame in a substantially horizontal plane, an endless cutter chain mounted on said cutter frame, a motor carried by said base frame, and driving connections whereby the power of said motor is caused to drive the said cutter chain and to move the supplemental frame laterally to feed said cutter chain.
34. In a mining apparatus, the combination with a wheel supported base frame adapted for transporting the mining apparatus, said base frame being adapted to be lowered to rest on and be supported by the floor of a mine chamber, kerf-cutting apparatus extending horizontally forward from said base frame in fixed relation to said base frame, and means comprising a bell crank lever for engaging the floor of the mine chamber at the rear end of said base frame to tilt the latter and vary the inclination of said kerf-cutting apparatus.
35. In a mining machine, the combination with a supporting frame, of three upright threaded supports mounted on said supporting frame at the angles of a horizontal triangle, cutter mechanism comprising a cutter frame mounted on said supports, nuts on the said supports, and means for simultaneously turning said nuts to secure rectilinear vertical adjustment of said cutter apparatus transversely thereof.
36. In a coal cutting machine, the combination with a movable supporting frame, of three spaced-apart vertical threaded supports on said supporting frame, coal cutting mechanism mounted on top of said supports with the periphery of said cutting mechanism in plan surrounding said supports, means on said supports for adjusting the elevation of

said coal cutting mechanism, and means for operating said coal cutting mechanism at its adjusted elevation.

37. In a coal cutting machine, the combination with a movable supporting frame, of three spaced-apart vertical standards extending upwardly from said supporting frame, three screw-threaded rods respectively extending into said standards, nuts mounted on 10 said standards and in threaded engagement with said screw-threaded rods, sprockets on said nuts, a sprocket chain engaging each of said sprockets, a horizontal kerf-cutter mounted on top of said screw-threaded rods, 15 means for driving said sprocket chain to rotate said nuts to secure simultaneous up or down movement of said screw-threaded rods and thereby adjust said kerf-cutter rectilinearly and vertically into various horizontal 20 planes, and means for operating said kerf-cutter at its adjusted elevations.

38. In a coal cutting machine, the combination with a movable base, of a supplemental frame mounted on said base for movement relatively thereto about a vertical axis and having a cutter frame extending horizontally in planes near the top of the said movable base, an endless cutter chain on said cutter frame, a motor on the base frame below the planes of the cutter frame, gearing for transmitting the power of the motor to drive the cutter chain, a winding drum on the base frame, a cable connected at one end to said drum to be wound thereon and adapted 30 to be connected at the other end to a point external to the machine, an additional motor connected to said drum to rotate the same and move the machine as a whole, means for adjusting the elevation of said cutter frame and 35 cutter chain relatively to said supplemental and base frames, and means for swinging said supplemental frame on said vertical axis to secure arcuate feeding movement of said cutter chain.

45. 39. In a wheel supported coal mining machine adapted to be transported over mine tracks to cut a horizontal kerf while resting on the floor of a mine chamber beyond the forward end of said track, the combination with 50 a base frame, of track wheels for supporting said base frame on the mine track during transportation of the whole machine, said wheels being detachable to permit said base frame to rest on the floor of the mine chamber 55 beyond the forward end of said track, rope winding mechanism mounted on said base frame and comprising a rope adapted to be connected to an anchorage for sliding the base frame over the floor of the mine chamber 60 to new positions, anchoring mechanism for holding the base frame in adjusted position, a supplemental frame pivotally connected to said base frame for lateral movement relatively thereto on an upright axis, dislodging 65 mechanism mounted on said supplemental

frame, and means for operating said dislodging mechanism including lateral arcuate movement of said supplemental frame.

40. In a system of coal mining apparatus comprising a ground supported track and a portable mechanism adapted to be transported over said track and beyond the forward end thereof for sliding support on the mine floor, and also adapted to cut a horizontal kerf in a coal face while supported on the mine floor in advance of said track, the combination with a rigid base frame, of wheels adapted to be connected to said base frame for transporting the machine over said mine track, a supplemental frame pivotally connected to said base frame for swinging movement relatively thereto on an upright axis, kerf-cutting mechanism on said supplemental frame extending horizontally to points outside of and remote from the vertical bounding lines of said base frame and its rear end extending back over the base frame, supporting connections between the rear end of said supplemental frame and the base frame comprising a horizontally extended rotary base structure pivotally disposed at the forward end of said base frame, power mechanism for driving the kerf-cutting mechanism, power mechanism constructed and arranged to move the supplemental frame laterally from points on one side of the machine to points at the other side thereof, and a motor on the base frame for actuating said power mechanisms.

41. In a mining machine, the combination with a main frame, of a supplemental frame pivotally mounted on said main frame for swinging movements relatively thereto on an upright axis, a horizontal kerf-cutter mounted on said supplemental frame for adjustment in elevation, means for holding the kerf-cutter at adjusted elevation, means for operating said kerf-cutter including swinging movement of said supplemental frame to secure feeding movement of said kerf-cutter, and breaking mechanism carried by said supplemental frame for operation in the kerf cut by said kerf-cutter to break down the slabs of material below the plane of said kerf-cutter.

42. In a mining machine, the combination with a main frame, of propelling mechanism therefor, a supplemental frame pivotally connected to said main frame for lateral swinging movement in advance thereof on an upright axis, means comprising a worm gear immovably secured to said main frame for swinging said supplemental frame relatively to said main frame on such upright axis, plane kerf-cutting mechanism comprising an endless cutter-chain mounted on said supplemental frame in position to cut a horizontal plane kerf substantially at right angles to said upright axis, means for driving said cutter chain, and means for operating said

propelling mechanism to effect rectilinear feeding movement of said kerf-cutting mechanism when extending laterally from one end of said main frame and while locked by said worm gear against turning relatively to said main frame to effect the cutting of a kerf to one side of the path of travel of said main frame and substantially parallel to such path of travel and in a plane substantially perpendicular to such upright axis.

43. In a mining machine, the combination with a main frame, of a supplemental frame pivotally connected thereto, horizontal kerf-cutting mechanism mounted on said supplemental frame, propelling mechanism for moving said main frame rectilinearly to effect rectilinear feeding movement of said kerf-cutting mechanism, means for swinging said supplemental frame to effect arcuate movement of said supplemental frame, and breaking mechanism mounted on said supplemental frame within the boundary of said kerf-cutting mechanism to act in the kerf cut by the latter to break down material adjacent said kerf.

44. In a mining machine, the combination with a main frame, of wheels adapted to support said frame on a mine track, a supplemental frame pivotally connected to said main frame to swing on an upright axis relatively thereto, kerf-cutting mechanism mounted on said supplemental frame, means for driving said kerf-cutting mechanism, means comprising a worm gear immovably secured to said main frame for swinging said kerf-cutting mechanism to secure lateral feeding movement thereof, and propelling mechanism for said main frame to move the latter along the mine track to effect rectilinear feeding movement of said kerf-cutting mechanism while said supplemental frame is locked by said worm gearing against turning movement relatively to said main frame.

45. In a mining machine, the combination with a main frame, of wheels for supporting said main frame on a track, horizontally extending kerf-cutting mechanism mounted to swing as a unit on an upright axis at the forward end of said main frame, means for driving said kerf-cutting mechanism, a worm gear immovably secured to said main frame for swinging said kerf-cutting mechanism as a unit relatively to said main frame, and propelling mechanism for moving said main frame along a track to secure forward rectilinear movement of said kerf-cutting mechanism when extending laterally from one side of said main frame and locked by said worm gearing against turning movement relatively to said main frame, and for effecting rearward rectilinear feeding movement of said kerf-cutting mechanism when the latter extends laterally from the other side of the forward end of said main frame and while said cutting mechanism is locked by said

worm gearing against turning movement relatively to said main frame.

46. In a system of coal mining devices comprising a track extending longitudinally toward the coal face, and mining mechanism thereon arranged to cut kerfs which extend across the central longitudinal vertical plane of the track, the combination of a wheeled truck resting on the track, of three vertically elongated guide supports respectively at the angles of a triangle in horizontal plan, a frame vertically adjustable connected to each of said guide supports independently of the others and forming a base in a relatively high plane, a kerf-cutter supported on said vertically adjustable frame and extending forward to points in front of the truck and adapted to be moved, while cutting, laterally across the longitudinal vertical planes of the truck, a motor directly on said truck, and means connected between said motor and said kerf-cutter to drive the latter and move the same laterally across the front end of said truck.

47. In a coal cutting machine, the combination with a rigid base frame, of a supplemental frame pivotally connected to said base frame, three triangularly arranged upright spaced-apart supporting devices fixedly mounted on said supplemental frame, a cutter-frame mounted on top of said devices with the space above and below one corner thereof free and unobstructed, means for adjusting the elevation of said cutter frame relative to said supplemental frame, an endless cutter-chain mounted on said cutter-frame to encompass the area of connection between said supporting devices and said cutter-frame, means for driving said cutter-chain, and means for swinging said supplemental frame to effect the arcuate feed of said cutter chain to cut material extending along said unobstructed space.

48. In a coal cutting machine, the combination with a movable base frame, of supporting track wheels therefor, a cutter apparatus movable as a unit with respect to the base frame about a normally vertical axis, and comprising kerf-cutting mechanism extending outwardly beyond the said base frame along normally horizontal lines near the uppermost plane of the machine, the said cutter mechanism being movable across one end of the machine about the said vertical axis through an arc extending at each side beyond the vertical plane of the corresponding track wheels, means comprising a worm gear concentric with said vertical axis and immovably secured to said base frame for swinging the said cutter apparatus about said vertical axis, said worm gearing being capable of locking the cutter apparatus to the base frame at any of several angles, means for driving said cutter apparatus, and means for moving the machine bodily while the cutter apparatus is

in operation and locked by said worm gear against turning.

49. In a wheel-mounted coal mining machine adapted to be transported over mine tracks and to cut a horizontal kerf in a coal face, the combination with a base frame, of track wheels for supporting said frame on a mine track, a supplemental frame carried by said base frame and mounted to turn in relation thereto in normally horizontal planes, continuously acting cutter devices carried by said turning supplemental frame and adapted when said frame turns to cut a horizontal kerf extending transversely across the track on which the machine stands, means comprising a worm gear immovably secured to said base frame for turning said last-named frame, said worm gearing when not driven being capable of locking said supplemental frame against turning, a motor for actuating said turning means, means for transporting the whole machine to secure rectilinear movement of said turning frame when extending from one side of said base frame and locked against turning by said worm gearing, and means for driving said cutter devices during such rectilinear feeding movement thereof.

50. In a mining machine, the combination with a main frame, of wheels for supporting the frame on a mine track, a supplemental frame pivotally connected to said main frame to swing relatively thereto on an upright axis, kerf-cutting mechanism mounted on said supplemental frame, a motor mounted on the main frame, power transmission mechanism between said motor and said kerf-cutting mechanism, means for vertically adjusting the kerf-cutting mechanism in horizontal parallelism and adapted to hold it either where it will form a kerf in relatively low horizontal planes or where it will form a kerf in other horizontal planes relatively higher than those aforesaid, and power-actuated mechanism connected between said motor and said supplemental frame and comprising worm gearing between the latter and said main frame, a worm wheel being fixed to the latter and a worm being on the supplemental frame in mesh with said worm wheel for causing the said kerf-cutting mechanism to be fed laterally across the front end of said main frame while said kerf-cutting mechanism is being driven.

51. In mining apparatus, the combination with a main frame, of wheels for supporting said frame on a centrally arranged track, a swinging supplemental frame pivotally connected to said main frame, a series of vertically elongated guide supports respectively at spaced-apart positions in horizontal planes forward of said main frame, a cutter frame connected to all of said guide supports and vertically adjustable thereon, and a horizontal kerf-cutter chain on said cutter frame

with its rear end adjacent upright lines extending through the forward end of said main frame, means for driving said cutter chain, and means for swinging said supplemental frame to effect arcuate feeding movement of said kerf-cutter chain. 70

52. In mining apparatus, the combination with a main frame provided with wheels for transportation on a mine track, of a supplemental frame pivoted thereto, a series 75 of elongated guide supports respectively spaced-apart in angular relation ahead of said main frame, a cutter frame connected to said guide supports and vertically adjustable thereon, an endless cutter chain on said cutter frame in position forward of vertical lines through the forward end of said main frame, and means for operating said cutter chain including feed thereof by swinging said supplemental frame transversely across the 80 longitudinal planes of said main frame to cut kerfs extending across the longitudinal vertical plane of the mine tracks. 85

53. In mining apparatus, the combination with a horizontal supporting frame, of an auxiliary frame comprising a plurality of posts extending upward from said supporting frame, a horizontal cutter frame supported on said posts at two adjacent sides leaving the cutting lengths and the space beneath the forward portion of the cutter frame, relative to feeding direction, free and unobstructed, an endless chain cutter on the cutter frame, means for operating said chain cutter including feed thereof, and breaking 90 mechanism following in the kerf cut by said cutter to break down the material before it is engaged by said auxiliary frame. 95

54. In mining apparatus, the combination with a main frame, of a conveyer thereon having a rear upwardly inclined portion extending from a hopper at the forward end of said frame, a supplemental frame pivotally connected to said main frame adjacent said hopper, a conveyer extending from a forward horizontal portion upwardly and rearwardly to deliver material into said hopper, an undercutter surrounding the horizontal portion of said second-named conveyer, dislodging mechanism above said undercutter, means 105 for swinging said undercutter, swinging conveyer and dislodging mechanism as a unit through one hundred eighty degrees or more while the conveyer thereof remains in delivery communication with said hopper, a rear 110 swinging conveyer mounted on the rear end of said main frame to swing through one hundred eighty degrees or more while remaining in communication with the intermediate conveyer on said main frame, a deep 115 hopper between the rear end of the intermediate conveyer and the lower receiving end of said rear conveyer, and means for pivotally supporting said rear conveyer and said deep hopper for free and unobstructed de- 120 125 130

livery of material into said hopper whether directed back to a mine car to load coal mined by said dislodging mechanism or directed to a gob to unload foreign material mined by 5 said dislodging mechanism.

55. In mining apparatus, the combination with a main frame, of a conveyer mounted thereon and inclined upwardly toward the rear, a hopper at the forward end of said 10 conveyer, a supplemental frame pivotally connected to the forward end of said main frame adjacent said hopper, an additional conveyer on said supplemental frame for delivering material into said hopper, kerf-cutting and breaking mechanism on said supplemental frame for dislodging material onto 15 said additional conveyer, said additional conveyer comprising pivotally connected sections to permit swinging of said supplemental 20 frame through an angle of one hundred eighty degrees or more and retain delivery communication between said additional conveyer and said first-named conveyer, and means for operating said dislodging mechanism including swinging of said supplemental 25 frame.

56. In a mining and loading machine, the combination with a main frame adapted to slide over the floor of a mine chamber, of 30 wheels adapted to be connected to said frame for transporting the same along a mine track, a hopper at the forward end of said frame, a conveyer extending upwardly toward the rear from said hopper, a motor under said 35 conveyer on said frame, a separate motor for driving said conveyer, means for anchoring said main frame to the floor of the mine chamber, a rear swinging conveyer pivotally connected to the rear end of said main frame 40 and extending rearwardly on an upward incline, a separate motor for driving said rear conveyer, a deep hopper in receiving communication with said first-named conveyer through a range of angular movement of said 45 rear conveyer of one hundred eighty degrees or more, framework for pivotally supporting said hopper to drive a free and unobstructed delivery space from said first-named conveyer throughout the swinging range of movement 50 of said rear conveyer, a supplemental frame pivoted to said main frame at the forward end thereof for swinging movement relatively to said main frame on an upright axis, a chain kerf-cutter mounted on said supplemental frame in position to cut a horizontal kerf at the base of an upright mine wall, an upper horizontal chain kerf-cutter spaced above said first-named kerf-cutter, means 55 for adjusting the elevation of said upper kerf-cutter, said upper kerf-cutter having an unobstructed opening therethrough for the passage of material from above the plane of the upper kerf-cutter to the space below such plane, means in said opening in the upper 60 kerf-cutter for breaking down cut material, 65

a conveyer mounted on the supplemental frame and having a horizontal receiving portion and a delivery portion extending rearwardly and upwardly to said first-named hopper, means mounted on the rear end of 70 said main frame for tilting the latter to adjust the position of said kerf-cutting mechanism, worm gearing between said main and supplemental frames for locking the kerf-cutters against rotation, propelling mechanism on 75 said main frame for effecting rectilinear feeding movement of said kerf-cutters when locked against swinging movement, means connected between said motor on the main frame and said worm gearing for swinging 80 the supplemental frame and the kerf-cutters and the conveyer thereon relatively to said main frame, and means between said kerf-cutters and the motor on the main frame for driving said kerf-cutters. 85

57. In a mining and loading machine, the combination with mechanism for cutting spaced-apart plane kerfs horizontally across a mine wall, of a frame for supporting said kerf-cutting mechanism for arcuate feeding movement, loading apparatus comprising a conveyer having superposed portions traveling in opposite directions and extending to a position back of said kerf-cutting mechanism and in position on said supporting means to 90 follow said kerf-cutting mechanism in its arcuate feeding movement, and an upright arcuate kerf-cutter mounted on said supporting means to operate at or near the inner ends of the kerfs produced by said first-named 95 kerf-cutting mechanism. 100

58. The combination with a kerf-cutter comprising a frame, of a breaking device, a pipe for mounting said breaking device in the plane of said frame, and means connecting said pipe to said breaking device to conduct the operating pressure medium thereto. 105

59. The combination with a kerf-cutter comprising a frame, of a fluid pressure breaking device, and a pipe for mounting said 110 breaking device in the plane of said frame and also serving to conduct the pressure medium to said breaking device. 115

60. The combination with a kerf-cutter adapted to cut an upright kerf in a mine vein spaced back from the working face, of an expandible dislodging device comprising a cylinder and a plunger, mounted on said kerf-cutter to move bodily therewith into the kerf cut thereby but operable independently of the feed of said kerf-cutter, a pipe mounted on said kerf-cutter and connected to said cylinder to hold the latter in predetermined 120 relation to said kerf-cutter and for limited movement relatively thereto with the outer surface of the plunger bearing against that wall of the kerf remote from said working face, and means for controlling the expansion 125 of the plunger from said cylinder toward 130

said working face to break the cut material from the unmined mass.

61. In a mining machine, the combination with a supporting frame, of a supplemental frame mounted on said supporting frame to swing laterally thereto, a pair of vertically spaced horizontally extending traveling endless chain cutters mounted on said supplemental frame, an upright kerf-cutter mounted on said supplemental frame in position to form a kerf substantially in vertical alignment with the inner edges of the kerf formed by said horizontally extending chain cutters, and pressure-exerting mechanism mounted 10 on one of the horizontal chain cutters.

62. In a mining machine, the combination with a supporting frame, of a pair of vertically spaced traveling kerf-cutters pivotally mounted on said frame for lateral movement 20 relatively thereto, means comprising an upright standard for connecting said kerf-cutters, and an upright kerf-cutter having the shape of a segment of an annulus and carried by said standard in position to cut a kerf between the kerfs cut by said pair of kerf-cutters.

63. The combination with a mining machine having a kerf-cutter at its forward end, of spaced-apart bell cranks pivoted to the 20 rear portion of said mining machine to occupy upright planes parallel to the longitudinal length of the machine, and mechanism for operating said spaced-apart bell cranks to adjust the height of the rear end of the 35 mining machine and therefore the inclination of said kerf-cutter at the forward end of the mining machine.

In testimony whereof I have signed my name to this specification, on this 17th day 40 of November, A. D. 1917.

EDMUND C. MORGAN.
